[57] CLAIM

The ornamental design for a handle for an electric outboard engine, as shown and described.

DESCRIPTION

FIG 1 is a perspective view of a handle for an electric outboard engine showing our new design;

FIG. 2 is a top plan view thereof the bottom being identical in appearance;

FIG. 3 is a right side elevational view thereof, the left side being identical in appearance;

FIG. 4 is a vertical sectional view thereof, taken along line 4—4 of FIG. 2;

FIG. 5 is a rear elevational view thereof; and

FIG. 6 is a front elevational view thereof.
